UNITED STATES PATENT OFFICE.

FRIEND W. SMITH, OF BRIDGEPORT, CONNECTICUT, ASSIGNOR TO THE BEASLEY SUPPLY COMPANY, OF NEW YORK, N. Y.

REGISTERING-WHEEL.

SPECIFICATION forming part of Letters Patent No. 406,312, dated July 2, 1889.

Application filed October 8, 1888. Serial No. 287,494. (No model.)

To all whom it may concern:

Be it known that I, FRIEND W. SMITH, a citizen of the United States, residing at Bridgeport, in the county of Fairfield and 5 State of Connecticut, have invented certain new and useful Improvements in Registering-Wheels; and I do hereby declare the following to be a full, clear, and exact description of the invention, such as will enable others 10 skilled in the art to which it appertains to make and use the same.

My invention relates to certain new and useful improvements in the construction of wheels—such as are used in registering—and 15 has for its object to so construct said wheels that they shall be exceedingly light, while at the same time a facing and background of celluloid or other analogous material may be utilized for carrying the numbers without 20 any danger of chipping or breaking.

With these ends in view my invention consists in the details of construction and combination of elements, such as will be herein-after fully set forth, and then specifically 25 designated by the claims.

In the accompanying drawings, Figure 1 is a sectional elevation of a register-lock embodying my improvement; Fig. 2, a detail perspective of my improved wheel shown in 30 said lock; Fig. 3, a vertical section of said wheel without the guide-flange for the “float-wheels” shown in said lock; Fig. 4, a view similar to Fig. 3, but showing the notched side face-plate extended above the celluloid 35 facing, the latter being perfectly plain and without notches; and Fig. 5, a central vertical section of a wheel, showing the celluloid ring confined between the side face-plates.

Similar letters denote like parts in the several figures.

In order to afford a practical illustration of the use of my wheel, I have shown the same in connection with an ordinary register-lock, but I will enter into no description of 45 said lock, as the latter forms no part of my present invention. In the construction of registering-wheels the use of celluloid or other analogous light material is very advantageous, in that the numbers may be readily 50 impressed therein, while the celluloid itself

is exceedingly light and affords an excellent background for distinguishing said numbers.

Celluloid wheels have heretofore been used in numbering and similar machines, but they are liable to be imperfect, and in use they often become chipped and broken, thus effectually subverting their utility.

My invention contemplates the construction of a wheel which has all the advantages of a celluloid wheel, and also obviates all 6c danger of breaking.

A is a metal bushing, and B a celluloid wheel shrunk thereon. C is a metallic face-plate rigid with said bushing and extending against one side of said wheel. D are notches 6f in the periphery of said plate, which afford grasping-shoulders for the pawl which acts to rotate the wheel.

When my improvement is used in the connection shown at Fig. 1, notches E are formed 7c within the periphery of the celluloid wheel for the accommodation of the operating-pawls F, which project from the float-wheels G, but these notches are wider than the notches D, so that it will be clearly seen that the force 75 necessary to turn the wheel is exerted directly against the face-plate and not against the wheel; also any sudden concussion or rough manipulation of the machine embodying my wheel is sustained entirely by the 80 metallic face-plate.

In Figs. 1 and 2 I have shown a guide-flange H on the bushing in order to afford a proper guideway I for the float-wheels G; but said flange is merely adjunctive to this particular 85 use of my improvement, and I do not wish to be circumscribed thereby, the gist of my invention resting in the broad idea of the protection of the celluloid wheel by the notched face-plate. If desired, said plate may extend on both sides of the wheel, as shown at Fig. 5; but this is unnecessary except when the wheel is to be operated from both sides.

Ordinarily the operating pawl or pawls need extend only within the notches D, and it is 95 therefore immaterial whether the wheel is notched or not.

In Fig. 3 I have shown the bushing without the flange, since the latter would be dispensed with in very many instances, and in Fig. 4 I 100

have shown a wheel the body whereof is cast integral with the side face-plate, the celluloid facing being a thin ring molded or shrunk on said body. In this last instance I would extend the face-plate C above the celluloid ring and form the notches in the periphery of said plate beyond said ring.

I claim—

1. A registering-wheel consisting of a metallic core and a celluloid facing, substantially as set forth.

2. A celluloid registering-wheel having a metallic bushing and a metallic side facing provided with notches, as set forth.

3. A registering-wheel having a facing of 15 celluloid, a bushing or hub of metal, and a notched metallic plate extending at right angles from said bushing or hub against the side of said facing, substantially as set forth.

In testimony whereof I affix my signature in presence of two witnesses.

FRIEND W. SMITH.
